UNITED STATES PATENT OFFICE.

VIRGIL RIGSBY, OF HEMPHILL, TEXAS.

MAGNETO-CONTACT.

1,376,162.

Specification of Letters Patent. Patented Apr. 26, 1921.

Application filed March 9, 1920. Serial No. 364,573.

To all whom it may concern:

Be it known that I, VIRGIL RIGSBY, a citizen of the United States, and a resident of the city of Hemphill, in the county of Sabin and State of Texas, have invented a new and Improved Magneto-Contact, of which the following is a full, clear, and exact description.

This invention relates to improvements 10 in magneto contacts, particularly to a contact which may be used to advantage with the usual type of Ford magneto. An object of the invention is to provide a contact which may be quickly and easily removed, 15 cleaned, and replaced, and also one which will not make short circuits between the contact and the magneto.

With these and other objects in view, the invention consists in certain novel features 20 of construction and combinations and arrangements of parts as will be more fully hereinafter described and pointed out in the claims.

In the accompanying drawings:

25 Figure 1 is a view in vertical cross section showing the device in operative position in connection with a Ford magneto.

Fig. 2 is a view in transverse section on the line 2-2 of Fig. 1.

30 A magneto casing 1 is furnished with an opening 1' to receive a tubular casing 2, which is provided with an annular flange 3 between its ends. The casing 2 at its inner end fits the opening 1' and the flange 3 forms a shoulder against the casing. The flange 3 is secured to the casing 1 by screws 4 projecting through the flange and screwed into the casing. The tubular casing 2 is 35 preferably made of fiber or other non-conducting material, thus obviating the possibility of a short circuit through the screws 4.

The tubular casing 2 is provided with internal longitudinal key-ways 6 to receive 45 external keys 8 on a tubular barrel 7. This barrel 7 is externally flanged at its lower end 9, and bears against the inner end of the casing 2 to secure the barrel in the casing.

50 The keys 8 are of general wedge shape longitudinally and the key-ways 6 are correspondingly shaped to receive them, so as to limit the longitudinal inward movement of the barrel in the casing.

55 The barrel 7 is internally screw-threaded at its upper end to receive the externally

screw-threaded reduced end 10' of a plug 10. A vertical guide pin 11 carried by the plug 10 projects downwardly, and has a spherical enlargement at its lower end. 60

A contact plug 12 is formed with a socket 13 which incloses the enlarged end 14 of the pin 11, and the plug 12 at its upper end has an internal annular flange 15 to prevent the plug from slipping off of the pin 11. 65

A screw-threaded binding post 16 is provided on the outer end of the plug 10, and receives a jam nut 17 which is screwed down upon the wire 18 to hold same tightly in place on the plug 10. 70

The plug 12 is maintained in contact with the lead 20 of the magneto 21 by means of the spring 19 located around the pin between the plug 10 and contact 12, exerting a continuous downward pressure on 75 the latter.

It will be understood that by merely removing the plug 10, the contact plug 12 may be readily lifted out, examined, and quickly replaced. In the event that any 80 foreign matter collects on or about the lead 20 it may be removed without difficulty while the plug is out.

Another advantage is found in the insulation of the contact by means of the fiber 85 casing, the danger of short circuits between the contact and the magneto casing being completely obviated.

Various slight changes might be made in the general form of the parts described 90 without departing from my invention, and hence I do not limit myself to the precise details set forth, but consider myself at liberty to make such slight changes and alterations as fairly fall within the spirit and 95 scope of the appended claims.

I claim:

1. A device of the character stated, comprising a non-conducting tubular casing, a tubular barrel secured within the casing, a 100 guide pin within the casing, and a movable contact carried by the guide pin.

2. A device of the character stated, comprising a tubular casing, a tubular barrel secured within the casing, a guide pin with- 105 in the barrel, an enlargement on the end of the pin and a contact plug having a socket therein receiving the enlarged end of the pin.

3. A device of the character stated, comprising a tubular casing having key-ways 110 therein, a tubular barrel within the casing,

external keys on the barrel fitting the keyways in the casing, an external annular flange on the lower end of the barrel engaging the end of the casing, a plug in the 5 outer end of the barrel, a guide pin on the plug within the barrel and a movable contact carried by a pin.

4. A device of the character stated, comprising a non-conducting tubular casing, a 10 barrel within the casing, means securing the barrel against movement within the casing, a plug screwed into the outer end of

the barrel, a guide pin carried by the plug, an enlarged end on the guide pin, a movable contact having a cylindrical socket therein 15 receiving the enlarged end of the pin, an annular internal flange in the upper end of the socket confining the enlarged end of the pin within the socket, a spring around the pin between the plug and the movable 20 contact exerting pressure on the contact, and means for securing the device to the casing of a magneto.
